MECHANICAL PENCIL

John P. Lynn, Chicago, Ill., assignor to Dur-O-Lite Pencil Company, Melrose Park, Ill., a corporation of Delaware

Application April 29, 1940, Serial No. 332,255

32 Claims. (Cl. 120—17)

This invention relates to mechanical pencils, and more particularly to the type of pencil which employs reciprocably operable lead feeding mechanism which acts to advance the lead by a step by step movement.

It is an object of this invention to provide an improved mechanical pencil which is so constructed that certain of the difficulties, which have been heretofore encountered in the operation and use of pencils of this type, are eliminated.

A further object of this invention is to provide a mechanical pencil which not only performs more satisfactorily in use but also is of a simplified and improved construction, and is one, the parts of which are capable of being manufactured by less expensive manufacturing operations and are capable of being more readily assembled at a reduced cost.

As a feature of this last stated object, the pencil of this invention is so designed and constructed that the high degree of precision which has heretofore been essential in the construction and assembly of the parts for the production of a commercial pencil, is materially reduced, with the result that the construction of this invention may be made by the usual operating methods now in vogue in the pencil industry generally, without incurring the danger of producing pencils which are inoperative or which operate imperfectly.

These and other objects are contemplated for this invention, as will be apparent from the more detailed description of the construction, operation and advantages of the illustrative examples hereinafter more fully set forth.

Many attempts have been made in the past to produce a satisfactory commercial pencil employing reciprocal mechanism for feeding the lead by a step by step movement. However, due to the inherent characteristics of this type of feeding mechanism, certain mechanical deficiencies inevitably have been encountered, with the result that pencils of this type have not attained the success which their theoretical facility of operation merits. The fundamental and practical difficulty which has been encountered in all pencils of this type is that of properly aligning the reciprocal parts in the manner necessary to the proper and timely engagement and release of a lead feeding clutch. Pencils of this type have usually employed a clutch which is required to grip the lead when the clutch is in a retracted position, to remain in gripped relationship therewith throughout the lead feeding

movement of the clutch, and to promptly and definitely disengage the lead at the extreme lower position of the clutch. Furthermore, the clutch is required to return to its original retracted position while in a disengaged condition and without liability of engaging or frictionally contacting the lead in any manner which might result in the unwanted retraction of the already advanced lead, or the retraction of the following lead which has not yet become engaged in the tip orifice. This action of the clutch must take place completely automatically and solely through the operation of the parts and must be caused to occur by a simple reciprocating movement of an actuating member which is usually at the top of the pencil and usually operated by the thumb of the user.

One of the difficulties heretofore encountered has resided in the inability to produce the necessary automatic clutch operation of the type above described, and this in turn has resulted from the inability to provide clutch actuating mechanism which is foolproof and which invariably operates without fail to hold the clutch in lead feeding engagement with the lead for the entire lead-feeding stroke, and to release and to remain out of engagement with the lead for the entire return stroke of the clutch.

Accordingly, a more specific object of this invention is to provide a new and improved mechanism involving the clutch and the clutch actuating means which at all times assures the desired and intended operation of the clutch in the manner above described.

In prior constructions, pencils of this type have usually employed a clutch composed of a plurality of clutch fingers having lead-engaging surfaces which are capable of being compressed, by means of a clutch actuating sleeve, into lead-gripping engagement. In such instances, the clutch actuating sleeve has been also called upon to maintain the clutch fingers in engagement with the lead during the feeding stroke thereof and, at the completion of the lead feeding stroke, to release the clutch usually by having its movement arrested by engagement with a stop, whereby to permit the clutch to continue its advancing movement so as to free itself of the constricting influence of the sleeve and to permit its disengagement and release of the lead. These prior art mechanisms required the clutch and the sleeve to be returned to their original positions without, however, permitting the sleeve to assume a position relative to the clutch, during such return movement, in which the actuating

sleeve would exert a constricting influence on the clutch members. If such accidental and unwanted relationship should inadvertently occur, it is apparent that an unwanted retraction of the lead would result.

The delicacy of the problem involved in producing a satisfactory pencil of this type will be better appreciated when it is realized that writing leads of the type employed are of relatively small diameter and are necessarily quite fragile. Accordingly, extreme care must be exercised in avoiding any strain which may cause the lead to become broken. Furthermore, the lead must be fed and advanced so that its forward end may be projected through the lead orifice at the extreme tip of the pencil, which requires that the lead feeding mechanism be maintained in alignment with the tip orifice itself. This requirement is all the more difficult of attainment because instead of the lead guide tube leading to and terminating in the tip orifice as in the conventional mechanical pencil feed, in this step by step construction the lead leaves the lead tube and clutch and then enters the tip orifice. In other words, there is a gap between the end of the clutch and the tip orifice which is bridged by the lead stick only. That this requirement is extremely demanding is emphasized by the fact that the tip orifice must exert a frictional drag on the lead itself, which necessitates that the tip orifice have a close engagement with the lead and this fact eliminates any possibility of clearance at the location of the tip orifice. Hence, the alignment must be relatively exact as no opportunity is afforded to provide tolerance by an enlarged orifice at the tip.

In addition to the foregoing, the delicacy of this problem is further evidenced by the fact that the automatic operation of the clutch actuating sleeve and the clutch must depend upon the establishment of relatively balanced forces which are required for the operation of the clutch actuating sleeve during the reciprocatory movement of the clutch feeding mechanism. That is to say, during the lead feeding stroke the force which causes the clutch sleeve to remain in position and to maintain the clutch in engagement with the lead must be unimpaired and at the same time sufficient at all times to prevent the accidental disengagement of the clutch during the feeding stroke. On the other hand, an opposite force must be established which operates to return the clutch sleeve to its original position on the return stroke of the mechanism, which, in turn, must be sufficiently strong to avoid the liability of the clutch sleeve assuming the unwanted clutch engaging relationship to the clutch. These forces are opposite forces and may be influenced or entirely overcome by unwanted or unintended friction between the parts, or they may be altered or impaired by dirt, wear or other conditions which may be met during the normal operation and use of the pencil.

In the past, effort has been made to meet the problem of alignment by providing a multiplicity of aligning surfaces in order to attain accurate alignment of the parts functioning to feed the lead. This method of approach, however, has involved certain additional disadvantages resulting from the fact that perfect alignment of such a large number of surfaces has been impossible without resorting to prohibitive manufacturing costs. Furthermore, the use of a multiplicity of aligning surfaces has introduced into the pencil structure unwanted frictional resist-

ances which have made it almost impossible to maintain the required balance of forces upon which the successful operation of the pencil depends. In other words, slight misalignment of the engaging surfaces between the stationary pencil parts and the clutch actuating sleeve is apt to cause unwanted friction which sometimes entirely overcomes the required operating forces, with the result that in use the clutch may either let go of the lead too soon or, on the other hand, the clutch may engage the lead on the return stroke to cause an unwanted retraction of the lead. Having provided the guiding surfaces and encountered the unwanted frictional disturbances mentioned, some constructions have provided other means, in one instance a latch and in another a return spring, to more securely hold in position a clutch locking member during one or both of its directions of travel. It is obvious that such procedure merely strengthens one of two opposing forces which does not infallibly solve the problem.

Furthermore, in previous constructions the parts which include, respectively, the stationary surfaces which contact and guide the surfaces of the reciprocating parts, and the lead orifice, are usually supplied in two or more assembled parts which make it necessary to attempt to align the bores of those parts with each other. Consequently, alignment of the reciprocating parts, delicate in itself, has also depended on alignment of guiding surfaces for those parts.

With this understanding of the problems involved in the production of a pencil of this type, it may be stated that a further object of this invention is to provide a mechanical pencil of the step by step feeding type in which the parts which serve to actuate the lead are held in and are guided by the tip itself, with the result that the tip, which may be constructed as a single integral member provided with a lead orifice, may be formed by a single machining operation to provide a single guiding surface in accurate alignment with the tip orifice, and in which the single guiding surface so provided is solely depended upon for aligning and locating the lead feeding mechanism.

Furthermore, it is a feature of this invention to provide for the aligning of the lead actuating mechanism by a single surface in the tip, as aforesaid, by causing the aligning engagement to take place between the aligning surface and a portion of the lead feeding mechanism which is removed from the clutch as well as the clutch actuating sleeve, or, in other words, a portion which is removed from those parts which must be delicately adjusted and actuated for the automatic clutch operation. This feature results in a construction wherein a clutch and a clutch actuated sleeve are held in the tip in spaced relation to the walls of the bore of the tip, whereby no friction can occur therebetween, nor can the operation thereof be influenced by dirt, wear or other disturbing influence.

Another feature of this invention relates to the novel construction of clutch and clutch actuating sleeve assembly, in which the clutch actuating sleeve is mounted on and frictionally carried by the clutch itself and at the same time is spaced from the surfaces of the stationary parts of the pencil. This feature results in the clutch actuating sleeve at all times being carried in the proper associated relationship with the clutch and avoids the necessity for maintaining delicately balanced forces heretofore inherent in this type

of pencil. According to this invention, the clutch actuating sleeve is carried by a spring friction grip on the clutch itself, which grip is removed from that portion of the clutch sleeve which engages and actuates the clutch fingers. As a result, whenever the clutch sleeve is free to move with the clutch in either direction of travel—that is to say, whenever its movement is not arrested by a positive stop built into the pencil construction—the sleeve necessarily is caused to move 10 bodily with the clutch without permitting any relative movement therebetween such as would result in the imperfect operation of the pencil.

The nature of this invention and the simplicity and utility of its construction, as well as the soundness of the principles employed, will be apparent to those skilled in the art from a study of the illustrative disclosure of the preferred forms thereof illustrated in the accompanying drawings and hereinafter described in detail.

In the drawings—

Figure 1 is an enlarged view of a pencil, partly in cross section, constructed in accordance with one preferred embodiment of this invention.

Figure 2 is an enlarged cross sectional view illustrating the tip and operating mechanism of the tip embodied in Figure 1.

Figure 3 is a view similar to Figure 2 except that the lead actuating mechanism is in its maximum retracted position instead of the forward lead feeding position as shown in Figure 2.

Figure 4 is an exploded view of various parts constituting the lead feeding mechanism.

Figure 5 is a cross sectional view taken on the line 5—5 of Figure 2 and looking in the direction 35 of the arrows.

Figure 6 is a cross sectional view taken on the line 6—6 of Figure 2 and looking in the direction of the arrows.

Figure 7 is an elevational view of the tip and integral shank therefor illustrated in Figure 1.

Figure 8 is a cross sectional view of the tip, lower portion of the barrel, and lead actuating mechanism of a somewhat modified form of the present invention.

Figure 9 is a cross sectional view of a further modified form of this invention; and

Figure 10 is a still further modification which is similar to the construction shown in Figure 9, with the exception, however, that the body and tip are made integrally in a single piece.

Referring to the drawings, and particularly to Figures 1 to 7 thereof, it will be noted that this illustrative embodiment of the invention comprises a tip 10 having a tapered exterior surface 11 and a slotted end 12 provided with a tip orifice 13 in which the lead is frictionally held and through which the lead is projected to writing position. In this form of the invention, the tip is provided at its upper portion with an upwardly extending shank 14 provided with screw threads 15 for a purpose hereinafter described. The tip and shank are provided with a central bore 16 preferably, but not necessarily, of cylindrical formation, which communicates at its lower end with a second bore 17, as shown in Figure 2. Inasmuch as the cylindrical bore 17 is of less diameter than the bore 16, a stop-shoulder 18 is provided, for a purpose hereinafter more fully described. The bore 17 preferably terminates at its lower end with converging wall surfaces 19, which provide a funnel-shaped recess for the lead leading toward the pencil orifice 13.

The lower portion of the upwardly extending

shank 14 is preferably provided with a cylindrical surface 20 which receives the lower portion of a pencil barrel or body 21, substantially as shown in Figure 2. The barrel may be formed of any suitable construction but is here illustrated as comprising a metallic lining member 22 and an exterior decorative shell or covering 23. It is apparent, however, that the barrel may be made entirely of metal or of a non-metallic material as may be desired.

The upper portion of the barrel is provided with an internal bore of relatively large diameter which terminates at its lower end with an internal tapered surface 24, which, in turn, terminates in a lower cylindrical surface 25 which engages the cylindrical surface 20 on the lower portion of the tip shank. At the base of the tapered surface 24, on the inside of the barrel, a shoulder 26 is provided which, when the barrel is on the tip, is positioned adjacent the lower portions of the threads 15 on the shank.

In the interior of the pencil barrel a specially constructed nut 27 is provided which has a depending skirt portion 28 having internal threads adapted for threaded engagement with the threads 15 on the upper part of the tip shank. The lower portion of the threaded skirt provides an edge 29 adapted to have engaging abutment with the shoulder 26 on the interior of the barrel, whereby when said nut is screwed up tightly, the barrel is clamped between the end 28 of the nut and the shoulder 30 of the tip located at the base of the shank. It will be apparent that the exterior surface 20 at the base of the shank may be machined in definite concentric relationship to the outside tapered surface of the tip, whereby an accurate alignment of the tip and tapered portion of the barrel may be readily produced. It should be noted that while alignment of the tip and barrel is desirable for proper exterior appearance of the pencil, precise alignment of the tip and barrel, with respect to their internal surfaces, is not required for proper functioning of the mechanism of this invention.

The sole necessary guiding influence for the reciprocating parts is within the tip and such parts as extend upward from the tip may be free of guiding influence with the barrel and free of surface contact with the nut 27. It will be apparent that this construction serves to provide a firm holding and clamping means for maintaining the barrel and the tip of the pencil in assembled relation and at the same time permits the tip to be removed by merely turning the tip relative to the pencil barrel. When turning the tip on and off of the nut, it is preferable to exert pressure on the nut in maintaining it on the shoulder 26, as hereinafter more fully described, so as to maintain the nut against rotation relative to the barrel, whereby the tip may be screwed on and off of the nut as desired.

The upper portion of the nut 27 is preferably of a special construction, as represented in Figure 2, whereby it serves as a seat for the spring 31 without, however, exerting any guiding influence on the lead guide tube to be presently described. Accordingly, the nut is provided with a central orifice 32 which is of substantially larger diameter than the lead guide tube which passes therethrough, so that no holding or aligning influence is exerted by the nut on the lead guide tube. Furthermore, it is to be noted that the skirt 28 of the nut is somewhat longer than the corresponding threaded portion of the shank 75 of the tip so that when the nut and the tip are

firmly screw together in tight holding engagement with the barrel, a space 33 is provided between the base of the head of the nut and the upper edge of the shank of the tip. The purpose and utility of this space will be described more fully below.

Mounted in the upper end of the barrel is a cylindrical member 34 which may be formed of metal and which serves as a spare lead magazine. This magazine is preferably provided with a base member 35 which terminates in a downwardly extending portion 36 having an internal thread 37 therein into which is threaded the upper end of the lead guide tube 38. This base member is preferably provided with a dished upper surface 39 terminating in a slightly enlarged recess 40 which serves to cause the leads to successively feed one after the other into the lead guide tube when the pencil is employed in normal operation. The base member is also provided with a shoulder 41 which serves as the upper seat for the spring 31. The base is connected to the magazine 34 by any suitable means, as by crimping in the manner represented at 42.

The magazine is also preferably provided with an inwardly projecting ridge 43 which serves to hold the spare leads 44 out of close engagement with the walls of the magazine, particularly at the bottom thereof, so as to maintain them in a position which causes them to more readily move into the recess 40 and adjust themselves in aligned position for automatic feeding into the lead guide tube.

The lead guide tube 38 has a bore capable of receiving lead sticks successively, one after another, and extends downwardly in the manner shown in Figure 2 through the enlarged opening 32 of the nut and projects into the bore 16 of the tip. The lead guide tube is preferably provided with slots at its extreme end which extend partially up the length thereof so as to constitute a plurality of clutch fingers. In consequence, the lower end of the lead guide tube is referred to herein as the "clutch" as distinguished from the lead guide tube itself, but it is to be understood that this construction may be formed of two separate parts suitably connected together, or may be formed integrally from a single tube of metal, as herein illustrated.

The clutch fingers at their ends are preferably somewhat thickened, as at 45, and are provided with serrated inner surfaces in the usual manner, whereby good gripping of the lead may be obtained when the clutch fingers are pressed inwardly toward the lead. Furthermore, the clutch fingers are sprung slightly outwardly whereby their normal tendency is to remain in a position in which they are free from engagement with a lead positioned therebetween, but whereby their resiliency is such that the clutch fingers are subject to being compressed inwardly to effect the desired gripping of the lead. The thickened portion 45 of the clutch fingers are preferably tapered outwardly and downwardly, as shown at 46, for suitable cooperation with the clutch actuating sleeve 47 in a manner hereinafter more fully described.

Mounted within the bore 16 of the tip is the reciprocating guiding and spacing sleeve 48 which is provided with an external surface 49 fitting within the bore 16 of the tip and an internal surface 50 which receives and locates the lead guide tube whereby to maintain the same in proper alignment within the tip bore. The upper por-

tion of the guiding and spacing sleeve 48 is preferably provided with diametrically opposed slots 51-51 which are clearly shown in Figures 2 and 4, which slots receive the wings 52-52 formed at diametrically opposed locations on the exterior of the lead guide tube 38. The slots 51-51 are preferably made of a width relative to the thickness of the wings 52-52, whereby a slight frictional drag is provided therebetween, so that reciprocation of the lead guide tube causes a corresponding reciprocation of the guiding and spacing sleeve throughout the extent of its possible travel.

The upper edge of the guiding and spacing sleeve is provided with an outwardly extending shoulder 53 which is adapted to abut the upper edge of the tip shank when the guiding and spacing sleeve is moved downwardly to its maximum lower position. The upper edges of the shoulders 53 are also adapted to engage the underside of the nut 27 when the guiding and spacing sleeve is moved through the space 33 to its maximum upward position. The lower end of the guiding and spacing sleeve is preferably, but not necessarily, provided with a conical recess 54 which is adapted to receive and center the clutch actuating sleeve 47 when the latter is in engagement therewith, by cooperation with the conical tapered upper edge 55 of the clutch actuating sleeve 47. These conical surfaces are formed at such an angle that no wedging action between these parts can occur.

As clearly shown in Figures 2 and 3, the clutch and clutch actuating sleeve assembly which is here illustrated comprises a clutch actuating sleeve 47 formed at its upper end with a cylindrical surface 56 which has an internal diameter substantially the same as that of the lead guide tube. The remaining portion of the clutch actuating sleeve is provided with an enlarged bore 57 which provides clearance for the expansion of the clutch fingers under their inherent resiliency when the clutch sleeve is moved upwardly relative to the clutch. The lower portion of the bore 57 terminates in an outwardly flaring tapered surface 58 which is given an angularity corresponding to that of the outwardly tapering surfaces 46 of the clutch fingers, whereby when the clutch is moved into the clutch actuating sleeve 47 these surfaces come into engagement and, through their wedging action, exert a constricting influence on the clutch fingers to cause the spring fingers to grip the lead. The tapered surfaces 46 and 58 are so formed as to exert a definite tendency on the clutch actuating sleeve to maintain the clutch fingers in compressed or clutching engagement throughout the entire downward stroke, or, in other words, until the clutch actuating sleeve is definitely and positively removed from its constricting relationship to the clutch fingers by means of its engagement with the stop shoulder 18 in the bore of the tip. It is to be particularly noted that the clutch actuating sleeve 47 has an external diameter substantially less than the diameter of the bore of the tip in which it is disposed, whereby the clutch actuating sleeve is free to reciprocate within the tip without deriving any alignment from the tip bore and without having any frictional engagement therewith. Furthermore, the clearance is sufficient to avoid any such engagement or interference due to the presence of dirt or other foreign particles.

It is also to be observed (see Figure 3) that when the lead feeding mechanism is in its maximum retracted position, the clutch fingers 45 are

in gripping engagement by virtue of the fact that they have been moved upwardly into the bore 57 of the clutch actuating sleeve and that the upper end of the clutch actuating sleeve has, in turn, been moved into the conical recess 54 of the guiding and spacing sleeve 48, and that all of these parts have been brought to rest by virtue of the fact that the collar 53 at the upper end of the guiding and spacing sleeve has been brought into abutment with the lower surface of 10 the nut 27.

With the parts so related, further upward movement thereof is prevented and the tension of the spring 31, which is tending to urge the parts further upwardly, is exerted through the 15 various abutting and wedging surfaces to hold the clutch fingers in intimate and firm gripping relationship on the lead. On the other hand, when the lead guide tube is thrust downwardly by virtue of a propelling thrust being applied to the 20 lead magazine from the upper end of the pencil, the initial downward movement of the lead guide tube causes the guiding and spacing sleeve 48 to move bodily with it through the frictional dragging action of the wings 52—52 in the slots 51—51. 25 As a consequence, the forward movement of the lead guide tube causes its own bearing and supporting member to be moved forward with it so as to eliminate the otherwise unavoidable necessity of causing the lead guide tube to project beyond its bearing surface an increased amount. By virtue of this construction, an accurate and satisfactory alignment of the lead guide tube is maintained through the instrumentality of a single guiding bearing surface which is mounted in the tip itself and which, through reciprocation, is enabled to guide and support the lead guide tube throughout a greater portion of its length than would otherwise be possible. Furthermore, the reciprocating guiding and spacing sleeve avoids the necessity of an unduly long guiding and bearing surface such as would otherwise project downwardly into the tip an amount which would interfere with the intended and desired operation of the clutch actuating sleeve.

It will be apparent that upon the continued downward movement of the lead guide tube, after the same has traveled a distance equal to the space 33 between the base of the nut and the top of the tip shank, the shoulder 53 on the upper edge of the guiding and spacing sleeve 48 will abut and be arrested by the upper edge of the tip shank. At the time this occurs, however, the wings 52—52 of the lead guide tube are spaced somewhat above the base of the slots 51—51, whereby the lead guide tube with its wings is free to continue its downward movement, notwithstanding the fact that the guiding and spacing sleeve has come to rest. Before the wings reach the base of the slots, however, continued downward movement of the lead guide tube next causes the base of the clutch actuating sleeve 47 to abut against and be stopped by the stop shoulder 18 within the bore of the tip, so that the clutch actuating sleeve is caused to remain stationary during the final downward movement of the lead guide tube and the clutch. The stopping of the clutch actuating sleeve also occurs before the wings on the lead guide tube reach the bottom of the slots 51—51, so that the lead guide tube is free to undergo a further downward movement which ultimately brings the parts to their final advanced position shown in Figure 2, in which position the wings are in 75

engagement with the bottom of the slots and all downward movement is finally arrested.

At this point, however, the downward movement of the clutch, beyond that of the clutch actuating sleeve 47, is sufficient to release the clutch fingers from the constricting influence of the clutch actuating sleeve, whereby the clutch fingers, through their inherent resilience, are free to move outwardly within the clearance 57 of the clutch actuating sleeve and to thus disengage the lead so as to be entirely free therefrom. It is to be particularly noted that upon the release of the clutch fingers from engagement with the lower surface 58 of the clutch actuating sleeve, that the clutch fingers are free to spring outwardly by their inherent resilience and that inasmuch as the friction surface 56 at the upper portion of the clutch actuating sleeve engages the clutch at a point below the upper extremity of the slots between the fingers, the outward movement of the fingers causes a positive spring frictional gripping action to occur between the upper portion of the clutch member and the friction surface 56 of the clutch actuating sleeve. This positive spring frictional grip binds and holds the clutch actuating sleeve in that position relative to the clutch which it occupies at the time the clutch releases the lead, or, in other words, in the position illustrated in Figure 2, whereupon, by an upward movement of the parts, the return movement of the lead guide tube and clutch immediately exerts a corresponding return movement on the clutch actuating sleeve, with the result that the same is moved upwardly at the same rate, with the avoidance of any accidental clutching engagement between the clutch fingers and the lower end clutch actuating sleeve. In consequence, the clutch fingers are maintained in disengaged relationship to the lead throughout its entire upward movement, or, in other words, until such time as the guiding and spacing sleeve 48 abuts the lower portion of the nut and the upper end of the clutch actuating sleeve abuts the lower portion of the guiding and spacing sleeve. When the parts have been so arrested, the clutch fingers, through their continued return movement, are once more forced into the lower portion of the clutch actuating sleeve to again effect and maintain a firm gripping action on the lead whereby the parts are in proper position for the next feeding stroke.

It will be noted particularly that the clutch actuating sleeve of this invention affords an entirely automatic and foolproof device for causing a gripping and release between the clutch and the lead in a positive, satisfactory manner as required for pencils of this type.

It will further be noted that the clutch actuating sleeve is free from guiding relationship with the bore of the tip or any other stationary part of the pencil, but on the contrary, that it is free to travel with the lead guide tube throughout the extent of its movement and is maintained in operative position thereon by a spring frictional grip which exerts a positive holding action both on the downward and return strokes.

It will further be noted that the spacing and guiding sleeve 48 serves as the sole guiding means for the reciprocating lead feeding parts, and that this sleeve is located within the tip itself and is given an increased guiding influence by virtue of its reciprocatory movement with respect to the tip.

It is to be understood that the upper end of

the pencil mechanism is held in position within the upper portion of the barrel of the pencil by virtue of the engagement of the magazine with the inner surface of the pencil barrel; but this positioning contact does not materially influence the guiding and aligning influence afforded by the guiding and spacing sleeve 48 mounted directly in the tip itself. The positioning contact between the upper portion of the barrel and the lead magazine is removed from the tip the maximum possible distance, whereby any minute variations that may inadvertently and occasionally occur may be taken up within the relatively great length therebetween, which will avoid any bending or binding stresses being localized at any one point such as would impair or interfere with the operation of the pencil. Furthermore, proper functioning of the mechanism to feed the lead may be accomplished even if the walls of the magazine are out of contact with the walls of the pencil barrel. That is, the magazine portion may float with respect to the inner surface of the barrel without adversely affecting the feeding mechanism. However, for easy location of the cap member 60, which contacts the top of the magazine for actuating the stroke, it is preferable that the magazine have contact with the pencil barrel.

It will further be noted that by virtue of the employment of a metal lining for the barrel, relatively accurate alignment of the barrel throughout its length, with respect to the tip, can be more readily maintained, which minimizes any difficulty that may otherwise occur through warpage or bending of non-metallic barrel parts.

It is to be understood further than any suitable cap member 60 may be employed on the upper end of the pencil, which, for convenience, may be in the form of an eraser or a finishing cap, and which will have abutting engagement with the lead magazine whereby a downward thrust imparted thereto by the operator may be, in turn, imparted through the lead magazine to the lead guide tube.

It will also be observed that when no lead is in the pencil, so that the upward movement of the pencil parts is not arrested by the constricting and gripping action of the clutch fingers, the parts will be free to move further upwardly only, however, until the wings 52-52 will be arrested by engagement with the lower surface abutment of the nut member 27. In this connection it will be noted that the height of the wings is greater than the space between the shoulder 53 of the guiding and spacing sleeve 48 and the lower surface of the nut 27, so that when the wings are arrested by the lower surface of the nut, as above indicated, the wings will not move out of the slots, which would necessitate dismantling the pencil for the reinsertion of the wings in the slots.

In addition to the foregoing, it will be noted that the lead-propelling mechanism may be assembled as a unit and inserted into the barrel of the pencil from the upper end thereof and caused to project from the lower end of the barrel so as to readily receive the tip. With the lower end of the mechanism projecting from the barrel, the tip may be placed in proper position, and when a slight pressure is exerted on the upper end of the mechanism so as to hold the nut 27 in firm engagement with the shoulder 28, the tip may be readily threaded thereon so as to clamp the tip on the barrel in firm assembled relationship.

It is further to be noted that the nut 27, by 75

virtue of its enlarged central opening 32, avoids any contact with the lead guide tube, whereby the aligning influence of the reciprocable guiding and spacing sleeve 48 is not impaired or interfered with, as the lead guide tube is free to assume such position with respect to the nut as may be required for the proper alignment of the lead guide tube with respect to the reciprocating guiding and spacing sleeve.

Referring now to the modification shown in Figure 8, it will be noted that the parts are substantially the same, except that a tip 10 is provided without an upwardly extending shank thereon. However, in addition to the bores 16 and 17, respectively, in the tip, a third enlarged and threaded bore 18 is provided which is adapted to receive a holding member 11 having threads 12 at the base thereof engaging with the threads of the tip. The member 11 is of somewhat modified construction in that it is of greater length than the nut 27 and is provided with a shoulder 13 which engages the tapered surface 14 provided in the barrel 15. The upper portion of the shoulder 13 forms a seat for the compression spring 16 in substantially the same manner as that illustrated in the other modification of the invention. Here, again, however, the member is provided with an enlarged bore 17 which is of a diameter substantially greater than the outside diameter of the lead guide tube 18, whereby the member does not exert any aligning or guiding influence on the lead guide tube. In this form, also, there is a reciprocating guiding and spacing sleeve 19 together with a clutch actuating sleeve 20. The reciprocating guiding and spacing sleeve 19 is guided and aligned entirely by the surfaces 16 of the tip bore which can be accurately machined with respect to the tip orifice 13 located at the base thereof. Similarly, the clutch actuating sleeve 20 is maintained in the bore of the tip, out of guiding relationship with the surfaces 16 thereof, so as to function in the manner described in connection with the modification illustrated in Figures 1 to 7, inclusive.

Referring now to the modification illustrated in Figure 9, it is to be noted that this form of the invention comprises a pencil tip 100 and a pencil barrel 101 which may be assembled in end to end abutment substantially as shown. The pencil tip is provided with a central bore 102 which communicates at its lower portion with a lower bore 103 and at its upper end with an enlarged bore 104. The bores 102 and 103 in this modification are substantially the same as the bores 16 and 17, respectively, of the modification illustrated in Figure 1 and provide therebetween a stop or step as shown. Furthermore, the bore 103 terminates in a tip orifice 105 for frictionally engaging the lead as it projects from the tip.

The upper enlarged bore 104 of the tip is internally threaded and serves to receive a tip anchoring member 106. This member is provided with a flange 107 which engages the shoulder 108 provided on the interior of the barrel 101. This shoulder is located at the bottom of the bore 109 in the barrel, which extends upwardly as shown in the drawings and terminates in an enlarged bore 110 adjacent the tip thereof.

The lead-propelling mechanism of this modification differs somewhat in construction from the corresponding mechanism illustrated in Figure 1, and yet the essential features of this invention are likewise embodied in this form. Here, however, the lead magazine is provided by means of a cylindrical member 111 which is constructed

to fit within the bore 109 of the barrel and which is provided at its lower end with a funnel-like or tapering base 112 which leads into the lead guide tube 113.

The lead guide tube 113 may be formed as an integral part of the lead magazine 111 or, if preferred, it may be formed as a separate part and attached thereto by any suitable means. The lead guide tube 113 extends downwardly and is preferably provided at its lower end with 10 threads 114 by which it is connected to the clutch member 115. Other form of attachment could be employed if desired.

The outside diameter of the clutch member 115 is slightly larger than the outside diameter 15 of the lead guide tube, whereby a stop shoulder 116 is provided by the upper edge of the clutch. The clutch, it will be noted, is formed from a tubular member which has a reduced outside diameter adjacent its lower portion, as shown at 20 117. Furthermore, it is provided with a plurality of longitudinal slots 119 which divide the tube into a plurality of resilient gripping fingers, substantially as in the other modifications. It will be particularly noted that the slots 119 extend upwardly on the clutch member beyond the upper limit of the reduced portion 117, whereby 25 a cylindrical surface 120 is provided thereon which constitutes a spring friction gripping surface for the clutch actuating sleeve hereinafter described. Each of the spring fingers terminates in an enlarged head 118 having an external tapering surface 121 for engagement with the inner lower surface of the clutch sleeve which acts to constrict the clutch fingers in the manner 30 previously described, when the clutch is moved into the clutch sleeve.

A clutch sleeve 122 is provided, disposed in surrounding relationship to the clutch and with the upper portion of its cylindrical surface in engagement with the surface 120 which constitutes a spring friction grip between the clutch and the clutch sleeve. By virtue of the reduced diameter at 117 on the clutch member, the lower portion of the clutch sleeve is left free from engagement with the clutch when the clutch is projected beyond the clutch sleeve, as when the clutch is pushed to its maximum advanced position. In the advanced position, it is to be understood that the inherent resiliency of the clutch fingers causes them to spring outwardly to release their gripping engagement with the lead, while at the same time causing the clutch sleeve to be frictionally gripped at the spring friction surface 120 which remains in engagement with the upper portion of the clutch fingers.

Adjacent the upper edge of the clutch is a reciprocating spacing and aligning sleeve 123 which is preferably formed as a split bushing or ring of the construction shown in the drawings. This ring is provided with a longitudinal slot 124, which constitutes the split therein, which is of sufficient width to permit the ring to be sprung slightly inwardly so as to cause it to have a constricting frictional engagement with the exterior of the lead guide tube. In assembling the pencil, the frictional engagement between the reciprocating spacing and aligning sleeve 123 should be greater than any possible friction between the exterior of said sleeve and the interior of the bore 102 of the tip. By this construction, the reciprocating spacing and aligning sleeve is caused to move with the lead guide tube in both directions of movement throughout the extent 40 of its possible travel.

It is to be noted that the upper edge 125 of the clutch sleeve comes into abutment with the reciprocating spacing and aligning sleeve 123 when the parts are in the maximum retracted position. It will further be noted that the reciprocating spacing and aligning sleeve 123 is brought into abutment with the bottom edge 126 of the tip anchoring member 106 when the parts are in the maximum retracted position.

The upper surface of the flange 107 of the member 106 constitutes a seat for the compression spring 127 which is seated at its upper edge on the collar 128, which is preferably provided with a conical upper surface which closely engages the portion 112 of the lead magazine.

A shoulder 130 is provided at the top of the pencil between the bores 109 and 110 of the barrel, which is adapted to receive the shoulder 131 of the enlarged end 132 of the lead magazine which forms the inward stop for the mechanism when a lead-advancing thrust is applied to the upper end 133 of the pencil.

The upper edge 134 of the clutch mechanism forms a stop limiting the outward movement of the pencil when no lead is positioned between the clutch fingers. Normally, the upward movement is arrested by the clutch fingers being wedged into the clutch sleeve and the parts being brought to rest in the position shown in Figure 9 of the drawings. However, when the inward movement of the clutch fingers is not restricted by a piece of lead, the upward movement can continue for a slight additional amount until the stop 134 is brought to rest by engagement with the under surface of the reciprocating spacing and aligning sleeve 123.

In this form, as in the other forms, it is to be noted that the member 106 has an enlarged bore which does not contact or exert any aligning influence on the lead guide tube. Furthermore, the clutch sleeve is out of contact with the bore surface of the tip as well as all other stationary parts of the pencil. The clutch sleeve, on the other hand, is carried frictionally by the clutch itself and is held to move therewith in the desired manner by means of a spring frictional gripping action between the interior surface of the clutch sleeve and the resilient outwardly sprung clutch fingers. It further will be noted that the entire alignment of the operating mechanism adjacent the tip of the pencil is effected by a single guiding means, the exterior of which is guided in a portion of the tip itself, whereby it may be accurately aligned with the tip orifice and whereby the parts are mounted in a manner to be free from possible misaligning influences by any other part of the pencil.

Furthermore, it is to be observed that in this form, as in the other forms, the spacing and aligning member reciprocates, whereby a spacing and aligning relationship is maintained between the member 123 and the lead guide tube throughout a substantial portion of the reciprocation movement. Thus, an unwanted projection of the lead guide tube and clutch beyond the spacing and aligning sleeve 123 is avoided.

Referring now to the modification shown in Figure 10, the internal mechanism is somewhat the same as that illustrated in connection with Figure 9 and accordingly the parts which are similar have been given corresponding reference numerals. One difference in this form resides in the unitary construction of the tip and barrel which, for identification, is given the numeral 140 on the drawings. In this form, the entire

mechanism may be inserted from the open upper end of the barrel and, by suitable turning movement, is locked therein by the threaded engagement between the threads on the member 106 and the threads 151 in the bore of the pencil body. This modification is included as an illustration of the adaptability of this invention, generally, to a pencil having a unitary body construction and, therefore, it is to be understood that any of the mechanisms shown in the other modified forms may likewise be adapted to a construction having a unitary barrel and tip. It is believed to be unnecessary to illustrate all such possible modifications.

Another difference illustrated in Figure 10, resides in the connection between the upper end of the lead guide tube and the lower end of the lead magazine, which, it will be noted, provides a slight relative transverse movement of the lead guide tube relative to the axis of the lead magazine. This construction permits the lead guide tube to take the exact aligned position which is provided for it by the spacing and aligning sleeve 123 and avoids any interference to such alignment by the confining influence of the barrel on the lead magazine, in those instances where the guiding surface of the barrel portion of the body may not be absolutely accurately aligned with the bore in the tip portion of the pencil.

As shown in Figure 10, the lead guide tube may be formed of a cylindrical metal sleeve 150 having a base member 151 therein having a dished upper surface and a central orifice 152 somewhat similar to the construction shown in Figures 2 and 3. The cylindrical sleeve 150 may be crimped or otherwise attached to the base member, as shown at 153. The base member has a recess 154 in its lower portion in which a sleeve 155 is threaded substantially as shown in the drawing. The sleeve is preferably provided with an internal recess 156 adjacent its upper end, whereby to provide a space 157 between the shoulder of the sleeve and the inner face of the recess of the base member 151. The sleeve 155 is adapted to surround the lead guide tube 158, but inasmuch as the opening in the sleeve is larger than the external diameter of the lead guide tube, the lead guide tube is free to have slight lateral movement with respect to the sleeve. The lead guide tube is preferably provided with a flange 159 at the top thereof which loosely fits within the space 157, whereby the lead guide tube is disposed in substantial alignment with the orifice 152 in the base member. The upper end of the lead guide tube may taper slightly outwardly to form a funnel-like end whereby the leads will be fed therein without liability of being stopped by the edge of the lead guide tube.

The orifice 152 in the base member is preferably made slightly larger than otherwise so as to provide the proper feeding action for the leads, notwithstanding the slight displacement of the upper edge of the lead guide tube, as may sometimes occur when the pencil is assembled. The flange on the upper end of the lead guide tube is engaged at top and bottom so that the lead guide tube is held against axial displacement with respect to the base of the lead magazine, but at the same time slight misalignment between the axes of the lead guide tube and the lead magazine is made possible.

It is to be understood that other means may be employed which will be equivalent to the means shown, and therefore the invention should be con-

structed as covering all forms which provide for a slight lateral movement between the lead guide tube and the lead magazine.

From the foregoing, it will be observed that the 5 entire alignment of the lead guide tube, clutch and other parts of the mechanism which operate to feed the lead, are guided and aligned entirely by the spacing and aligning sleeve 123, without any interference whatsoever by any other portion of the pencil, including the lead magazine.

It is to be understood that this construction, 10 which provides for a connection between the upper end of the lead guide tube and the base of the lead magazine in a manner which permits 15 slight axial displacement of the lead guide tube, may be applied to any one or all of the other modifications of this invention as shown in the other figures of the drawings.

It is to be further understood that the orifice 20 152 in the base member 151 is to be provided with a diameter which permits the proper feeding of leads notwithstanding the slight possible misalignment referred to, but at the same time should not be made so large as to make it possible 25 for two leads to enter the orifice at the same time or otherwise becomes stuck or jammed therein.

It is apparent that in all of these modifications the reciprocating guiding and spacing sleeve can be given any degree of reciprocation that may be preferred, depending upon the particular operation desired. By way of example, the clutch actuating sleeve 47 in the modification shown in Figures 1 to 7, inclusive, may be somewhat 30 shortened and the reciprocating guiding and spacing sleeve correspondingly lengthened, whereby the clutch member may be caused to project beyond the guiding and spacing member the minimum amount, as desired. In this way, 35 the actual guiding and aligning member for the reciprocating parts is brought much closer to the tip orifice than would otherwise be possible, while at the same time avoiding any interference 40 with the novel and improved clutch and clutch actuating assembly which is herein disclosed.

It is to be understood that this invention is not to be limited to the construction disclosed in the accompanying drawings, as other forms and arrangements of parts are contemplated for 45 this invention, as will be apparent to those skilled in this art. It is, therefore, intended to include all forms which are properly equivalents of the illustrated examples and which properly come within the scope of the appended claims.

50 In view of the fact that the improvements herein disclosed do not depend upon the pencil body being formed of a separable barrel and tip, the invention is not to be limited to such construction. When a removable tip is referred to, it will be defined as such in the claims; and when 55 a barrel which is removable from the tip is referred to, it will be referred to as a "barrel." On the other hand, in the broader claims which are intended to include an integrally formed tip and barrel, as well as separable barrel and tip construction, the portions, respectively, will be defined as the "tip portion" and the "barrel portion" of the pencil body, which expressions are intended to include the specified portions, irrespective of whether the pencil body is made in two parts or whether it is made integrally, as illustrated in Figure 10.

What is claimed is:

1. A mechanical pencil, comprising a pencil body having a tip portion and a barrel portion,

said tip portion having a lead orifice at the end thereof and having a guiding bore in proximity to said orifice, the barrel portion of said body having a bore therein communicating with said first-named bore, lead propelling mechanism mounted for reciprocation in the body of said pencil comprising a lead guide tube, lead gripping means mounted for reciprocation with said lead guide tube and an actuating sleeve for said gripping means, and a spacing and aligning sleeve disposed in the body of said pencil having aligning engagement with said lead guide tube and having aligning engagement with said first-named bore, said lead gripping means and actuating sleeve being disposed for reciprocation in the said first-named bore and being spaced from the interior surface thereof.

2. A mechanical pencil, comprising a pencil body having a tip portion and a barrel portion, said tip portion having a lead orifice at the end thereof and having a guiding bore in proximity to said orifice, the barrel portion of said body having a bore therein communicating with said first-named bore, lead propelling mechanism mounted for reciprocation in the body of said pencil comprising a lead guide tube, lead gripping means mounted for reciprocation with said lead guide tube and an actuating sleeve for said gripping means, and a spacing and aligning sleeve disposed in the body of said pencil having aligning engagement with said lead guide tube and having aligning engagement with said first-named bore, said lead gripping means and actuating sleeve being disposed for reciprocation in the said first-named bore and being spaced from the interior surface thereof, said spacing and aligning sleeve having frictional engagement with said lead guide tube and being adapted to reciprocate therewith in said first-named bore for a portion of the travel of said lead guide tube.

3. A mechanical pencil, comprising a barrel and a removable tip, said tip having a lead orifice at the end thereof and having a guiding bore formed therein in proximity to said orifice, a barrel having a bore therein disposed in communication with said bore of said tip when said barrel is held in assembled relationship with said tip, lead propelling mechanism mounted for reciprocation in said barrel and tip comprising a lead guide tube, lead gripping means mounted for reciprocation with said lead guide tube and an actuating sleeve for said gripping means, a spacing and aligning sleeve disposed in said tip having aligning engagement with said lead guide tube and having aligning engagement with the bore in said tip, said lead gripping means actuating sleeve being disposed for reciprocation in said first-named bore and being spaced from the interior surface thereof, and means for holding said barrel and tip in assembled relation.

4. A mechanical pencil, comprising a barrel and a removable tip, said tip having a lead orifice at the end thereof and having a guiding bore formed therein in proximity to said orifice, a barrel having a bore therein disposed in communication with said bore of said tip when said barrel is held in assembled relationship with said tip, lead propelling mechanism mounted for reciprocation in said barrel and tip comprising a lead guide tube, lead gripping means mounted for reciprocation with said lead guide tube and an actuating sleeve for said gripping means, a spacing and aligning sleeve disposed in said tip having aligning engagement with said lead guide tube and having aligning engagement with the bore in said tip.

bore in said tip, said lead gripping means actuating sleeve being disposed for reciprocation in said first-named bore and being spaced from the interior surface thereof, and means for holding said barrel and tip in assembled relation, said spacing and aligning sleeve having frictional engagement with said lead guide tube and being adapted to reciprocate therewith in said first-named bore for a portion of the travel of said lead guide tube.

5. A mechanical pencil, comprising a pencil body having a tip portion and a barrel portion, said tip portion having a lead orifice at the end thereof and having a guiding bore in proximity to said orifice, the barrel portion of said body having a bore therein communicating with said first-named bore, lead propelling mechanism disposed for reciprocation in the body of said pencil comprising a lead guide tube, lead gripping means mounted for reciprocation with said lead guide tube and an actuating sleeve for said gripping means, and a spacing and aligning sleeve disposed in the body of said pencil having aligning engagement with said lead guide tube and having aligning engagement with said first-named bore, said lead gripping means and actuating sleeve being disposed for reciprocation in the said first-named bore and being spaced from the interior surface thereof, said clutch having lead gripping portions and a friction surface removed from said lead gripping portions, said clutch actuating sleeve having a portion for actuating said lead gripping portions of said clutch and a friction surface, said friction surface of said clutch and said friction surface of said clutch actuating sleeve being adapted for frictional gripping engagement when said clutch gripping portions are released by said clutch actuating sleeve, whereby said clutch actuating sleeve is retracted by the retractive movement of said clutch.

6. A mechanical pencil, comprising a pencil body having a lead orifice at the tip portion thereof and a bore extending therethrough, lead propelling mechanism mounted for reciprocation in said bore adapted to project the lead through said orifice, said lead propelling mechanism comprising a lead guide tube, a plurality of outwardly sprung lead gripping fingers separated by longitudinal slots and each having a lead-engaging portion, an actuating sleeve for said fingers mounted thereon and having a finger-constricting portion and a friction surface independent of said finger-constricting portion, said friction surface being mounted on said fingers above the lead gripping portions thereof, and said friction surface of said actuating sleeve being adapted to be frictionally gripped and carried by said fingers when the finger-constricting portion of said actuating sleeve is out of engagement with said fingers.

7. In a mechanical pencil, in combination, a tubular barrel, a tubular member longitudinally reciprocable therein and having a lower portion formed as a slender lead guide tube, a tip having a bore and a lead orifice concentric therewith, a tip anchoring means in the lower end of the barrel for connecting said tip to said barrel, said tip anchoring means having a bore substantially larger than the diameter of the lead guide tube which passes therethrough, a spring fingered clutch carried by the lower end of the lead guide tube for reciprocation therewith, a clutch actuating sleeve for said clutch, a longitudinally reciprocable spacing and aligning sleeve for said lead guide tube, said spacing and aligning sleeve being

guided solely by the engagement of its outer longitudinal wall with the inner wall of the tip bore, and the longitudinal walls of the lead guide tube, the spring fingered clutch and the clutch actuating sleeve being disposed in spaced relationship with respect to the bore of the tip.

8. In a mechanical pencil, in combination, a tubular barrel, a tubular member longitudinally reciprocable therein and having a lower portion formed as a slender lead guide tube, a tip having a bore and a lead orifice concentric therewith, a tip anchoring means in the lower end of the barrel for connecting said tip to said barrel, said tip anchoring means having a bore substantially larger than the diameter of the lead guide tube which passes therethrough, a spring fingered clutch carried by the lower end of the lead guide tube for reciprocation therewith, a clutch actuating sleeve for said clutch, and a spacing and aligning sleeve for said lead guide tube within the tip and mounted slidably on the lead guide tube, said spacing and aligning sleeve being held in alignment solely by engagement of its outer longitudinal wall with the inner wall of the tip bore, and the longitudinal walls of the lead guide tube, the spring fingered clutch and the clutch actuating sleeve being disposed in spaced relationship with respect to the bore of the tip.

9. In a mechanical pencil, in combination, a tubular barrel, a tubular member longitudinally reciprocable therein and having a lower portion formed as a slender lead guide tube, a tip having a bore and a lead orifice concentric therewith, a tip anchoring means in the lower end of the barrel for connecting said tip to said barrel, a spring fingered clutch carried by the lower end of the lead guide tube for reciprocation therewith, a clutch actuating sleeve for said clutch, and a longitudinally reciprocable spacing and aligning sleeve for said lead guide tube, said spacing and aligning sleeve being guided solely by the engagement of its outer longitudinal wall with the inner wall of the tip bore, and the longitudinal walls of the lead guide tube, the spring fingered clutch and the clutch actuating sleeve being disposed in spaced relationship with respect to the bore of the tip.

10. In a mechanical pencil, in combination, a tubular barrel, a tubular member longitudinally reciprocable therein and having a lower portion formed as a slender lead guide tube, a tip having a bore and a lead orifice concentric therewith, a tip anchoring means in the lower end of the barrel for connecting said tip to said barrel, a spring fingered clutch carried by the lower end of the lead guide tube for reciprocation therewith, a clutch actuating sleeve for said clutch, and a spacing and aligning sleeve for said lead guide tube within the tip and mounted slidably on the lead guide tube, said spacing and aligning sleeve being held in alignment solely by engagement of its outer longitudinal wall with the inner wall of the tip bore, and the longitudinal walls of the lead guide tube, the spring fingered clutch and the clutch actuating sleeve being held in spaced relationship with respect to the bore of the tip.

11. In a mechanical pencil, lead feeding mechanism comprising a clutch having spring fingers which normally spring outwardly, said fingers being formed by slots of substantial length cut longitudinally in a tube, and a clutch actuating sleeve surrounding the clutch for cooperative association with said clutch, said clutch sleeve having two bores, the larger of which being in the

lower portion of the sleeve and being of a size to adapt it for constricting the clutch fingers when said sleeve is forced over said fingers and for providing clearance for the clutch fingers to spring outwardly when the clutch actuating sleeve is not in position to constrict the clutch fingers, and the smaller bore being located above the larger bore and being of the proximate size of the tube from which the fingers are formed, 5 said sleeve being reciprocable between upper and lower stops and in all positions disposed with its smaller bore below the top of said slots, whereby 10 spring frictional contact between said spring fingers and the inner wall of the smaller bore of the clutch actuating sleeve is established for holding said sleeve against dislodgment and is exerted in all relative positions of said clutch actuating sleeve, with respect to said clutch, 15 which are assumed during the operation of said 20 lead feeding mechanism.

12. A mechanical pencil, comprising a pencil body having a barrel portion and a tip portion, a lead orifice in said tip portion, a bore extending through said barrel and tip portions and communicating with said lead orifice, lead feeding mechanism mounted in said bore and adapted to reciprocate therein, including a lead guide tube, 25 a clutch and a clutch actuating sleeve, and a sleeve having spacing and aligning engagement 30 with said lead feeding mechanism and mounted for reciprocation in said bore.

13. A mechanical pencil, comprising a pencil body having a barrel portion and a tip portion, a lead orifice in said tip portion, a bore extending through said barrel and tip portions and communicating with said lead orifice, lead feeding mechanism mounted in said bore and adapted to reciprocate therein, including a lead guide tube, a clutch and a clutch actuating sleeve, 35 and a spacing and aligning sleeve for said lead guide tube and having aligning engagement with said bore, said spacing and aligning sleeve being adapted to reciprocate in said bore and adapted to reciprocate relative to said lead guide tube.

14. A mechanical pencil, comprising a pencil body having a barrel portion and a tip portion, a lead orifice in said tip portion, a bore extending through said barrel and tip portions and communicating with said lead orifice, lead feeding mechanism mounted in said bore and adapted to reciprocate therein, including a lead guide tube, a clutch and a clutch actuating sleeve, a spacing and aligning sleeve for said lead guide tube and having aligning engagement with said bore, 50 said spacing and aligning sleeve being adapted to reciprocate in said bore and adapted to reciprocate relative to said lead guide tube, and means establishing frictional engagement between said lead guide tube and said spacing and aligning sleeve whereby said spacing and aligning sleeve will reciprocate with said lead guide tube.

15. A mechanical pencil, comprising a pencil body having a barrel portion and a tip portion, a lead orifice in said tip portion, a bore extending through said barrel and tip portions and communicating with said lead orifice, lead feeding mechanism mounted in said bore and adapted to reciprocate therein, including a lead guide tube, a clutch and a clutch actuating sleeve, a spacing and aligning sleeve for said lead guide tube and having aligning engagement with said bore, 55 said spacing and aligning sleeve being adapted to reciprocate in said bore and adapted to reciprocate relative to said lead guide tube, and means establishing frictional engagement between said lead guide tube and said spacing and aligning sleeve whereby said spacing and aligning sleeve will reciprocate with said lead guide tube.

to reciprocate relative to said lead guide tube, means establishing frictional engagement between said lead guide tube and said spacing and aligning sleeve whereby said spacing and aligning sleeve will reciprocate with said lead guide tube, and stop means in the bore of said pencil limiting the reciprocating motion of said spacing and aligning sleeve in both directions of movement.

16. A mechanical pencil, comprising a pencil body having a barrel portion and a tip portion, a lead orifice in said tip portion, a bore extending through said barrel and tip portions and communicating with said lead orifice, lead feeding mechanism mounted in said bore and adapted to reciprocate therein, including a lead guide tube, a clutch and a clutch actuating sleeve, and a spacing and aligning sleeve for said lead guide tube and having aligning engagement with said bore, said spacing and aligning sleeve being adapted to reciprocate in said bore and adapted to reciprocate relative to said lead guide tube, said spacing and aligning sleeve having a slot therein, and said lead guide tube having means connected thereto extending into said slot and establishing frictional engagement with said spacing and aligning sleeve, whereby said spacing and aligning sleeve is caused to reciprocate with said lead guide tube.

17. A mechanical pencil, comprising a pencil body having a barrel portion and a tip portion, a lead orifice in said tip portion, a bore extending through said barrel and tip portions and communicating with said lead orifice, lead feeding mechanism mounted in said bore and adapted to reciprocate therein, including a lead guide tube, a clutch and a clutch actuating sleeve, a spacing and aligning sleeve for said lead guide tube and having aligning engagement with said bore, said spacing and aligning sleeve being adapted to reciprocate in said bore and adapted to reciprocate relative to said lead guide tube, said spacing and aligning sleeve having a slot therein and said lead guide tube having means connected thereto extending into said slot and establishing frictional engagement with said spacing and aligning sleeve whereby said spacing and aligning sleeve is caused to reciprocate with said lead guide tube, and stops in the bore of said pencil for limiting the movement of said spacing and aligning sleeve in both directions.

18. A mechanical pencil, comprising a barrel and a removable tip, said tip having a lead orifice in the end thereof and having a bore communicating with said orifice, said barrel having a bore in communication with the bore of said tip, a tip anchoring member in the bore of said barrel for holding said tip on said barrel and having a portion in spaced relation to a portion of said tip whereby to define a space therebetween, lead feeding mechanism mounted for reciprocation in the bores of said tip and barrel, and a spacing and aligning sleeve for mounting said mechanism in aligned relationship to said lead orifice, said spacing and aligning sleeve being mounted for reciprocation in said tip bore and having a portion for limiting said reciprocatory movement by engagement with the spaced portions of said tip anchoring member and tip, respectively.

19. A mechanical pencil of the construction defined in claim 2, further characterized in that said lead guide tube is adapted to have reciprocatory movement relative to said spacing and aligning sleeve.

20. A mechanical pencil of the construction defined in claim 4, further characterized in that said lead guide tube is adapted to have reciprocatory movement relative to said spacing and aligning sleeve.

21. In a mechanical pencil, in combination, a tubular barrel, a tubular member longitudinally reciprocable therein and having a lower portion formed as a slender lead guide tube, a tip having a bore and a lead orifice concentric therewith, a tip anchoring member in the lower end of the barrel for connecting said tip to said barrel, said tip anchoring member having a bore substantially larger than the diameter of the lead guide tube which passes therethrough, a spring fingered clutch carried by the lower end of the lead guide tube for reciprocation therewith, a clutch actuating sleeve for said clutch, and a spacing and aligning sleeve for the lead guide tube, said spacing and aligning sleeve being aligned solely by the engagement of its outer longitudinal wall with the inner wall of the tip bore, and the longitudinal walls of the lead guide tube, the spring fingered clutch and the clutch actuating sleeve being disposed in spaced relationship with respect to the bore of the tip.

22. In a mechanical pencil, in combination, a tubular barrel, a tubular member longitudinally reciprocable therein and having a lower portion formed as a slender lead guide tube, a tip having a bore and a lead orifice concentric therewith, a tip anchoring member in the lower end of the barrel for connecting said tip to said barrel, said tip anchoring member having a bore substantially larger than the diameter of the lead guide tube which passes therethrough, a spring fingered clutch carried by the lower end of the lead guide tube for reciprocation therewith, a clutch actuating sleeve for said clutch, and a spacing and aligning sleeve within the tip and for the lead guide tube, said spacing and aligning sleeve being held in alignment solely by engagement of its outer longitudinal wall with the inner wall of the tip bore, and the longitudinal walls of the lead guide tube, the spring fingered clutch and the clutch actuating sleeve being disposed in spaced relationship with respect to the bore of the tip.

23. In a mechanical pencil, in combination, a tubular barrel, a tubular member longitudinally reciprocable therein and having a lower portion formed as a slender lead guide tube, a tip having a bore and a lead orifice concentric therewith, a tip anchoring member in the lower end of the barrel for connecting said tip to said barrel, a spring fingered clutch carried by the lower end of the lead guide tube for reciprocation therewith, a clutch actuating sleeve for said clutch, and a spacing and aligning sleeve for the lead guide tube, said spacing and aligning sleeve being aligned solely by the engagement of its outer longitudinal wall with the inner wall of the tip bore, and the longitudinal walls of the lead guide tube, the spring fingered clutch and the clutch actuating sleeve being disposed in spaced relationship with respect to the bore of the tip.

24. In a mechanical pencil, in combination, a tubular barrel, a tubular member longitudinally reciprocable therein and having a lower portion formed as a slender lead guide tube, a tip having a bore and a lead orifice concentric therewith, a tip anchoring member in the lower end of the barrel for connecting said tip to said

barrel, a spring fingered clutch carried by the lower end of the lead guide tube for reciprocation therewith, a clutch actuating sleeve for said clutch, and a spacing and aligning sleeve for said lead guide tube within the tip and mounted on the lead guide tube, said spacing and aligning sleeve being held in alignment solely by engagement of its outer longitudinal wall with the inner wall of the tip bore, and the longitudinal walls of the lead guide tube, the spring fingered clutch and the clutch actuating sleeve being held in spaced relationship with respect to the bore of the tip.

25. A mechanical pencil, comprising a pencil body having a tip portion and a barrel portion, said tip portion having a lead orifice therein and a bore communicating with said orifice, and said barrel portion having a bore communicating with the bore in said tip portion, lead feeding mechanism mounted for reciprocation in the bores of said tip and barrel portions comprising a lead guide tube, a clutch having a clutch actuating sleeve, said clutch actuating sleeve being adapted to reciprocate relative to said clutch, and a spacing and aligning sleeve for said lead guide tube and having aligning engagement with the bore of said tip portion and being adapted to reciprocate relative to said bore and relative to said lead guide tube, said lead guide tube having frictional engagement with said spacing and aligning sleeve of sufficient holding force to cause said spacing and aligning sleeve to reciprocate with said lead guide tube throughout the extent of its possible travel, and said clutch actuating sleeve having frictional engagement with said clutch of sufficient force to cause said clutch actuating sleeve to reciprocate with said clutch through the extent of its possible travel.

26. A mechanical pencil, comprising a pencil body having a tip portion and a barrel portion, said tip portion having a lead orifice therein and a bore communicating with said orifice, and said barrel portion having a bore communicating with the bore in said tip portion, lead feeding mechanism mounted for reciprocation in the bores of said tip and barrel portions comprising a lead guide tube, a clutch having clutch actuating sleeve, said clutch actuating sleeve being adapted to reciprocate relative to said clutch, a spacing and aligning sleeve for said lead guide tube and having aligning engagement with the bore of said tip portion and being adapted to reciprocate relative to said bore and relative to said lead guide tube, said lead guide tube having frictional engagement with said spacing and aligning sleeve of sufficient holding force to cause said spacing and aligning sleeve to reciprocate with said lead guide tube throughout the extent of its possible travel, and said clutch actuating sleeve having frictional engagement with said clutch of sufficient force to cause said clutch actuating sleeve to reciprocate with said clutch through the extent of its possible travel, and stops in the bore of said pencil body limiting the travel of said spacing and aligning sleeve and said clutch actuating sleeve, respectively.

27. A mechanical pencil, comprising a pencil body having a tip portion and a barrel portion, said tip portion having a lead orifice therein and a bore communicating with said orifice, and said barrel portion having a bore communicating with the bore in said tip portion, lead feeding mechanism mounted for reciprocation in the bores of said tip and barrel portions comprising a lead guide tube, a clutch having a clutch

actuating sleeve, said clutch actuating sleeve being adapted to reciprocate relative to said clutch, and a spacing and aligning sleeve for said lead guide tube and having aligning engagement with the bore of said tip portion and being adapted to reciprocate relative to said bore and relative to said lead guide tube, said lead guide tube having frictional engagement with said spacing and aligning sleeve of sufficient holding force to cause said spacing and aligning sleeve to reciprocate with said lead guide tube throughout the extent of its possible travel, and said clutch actuating sleeve having frictional engagement with said clutch of sufficient force to cause said clutch actuating sleeve to reciprocate with said clutch through the extent of its possible travel, said spacing and aligning sleeve and said clutch actuating sleeve being adapted to have end to end abutment whereby said spacing and aligning sleeve arrests the movement of said clutch actuating sleeve in one direction of movement.

28. A mechanical pencil, comprising a pencil body having a tip portion and a barrel portion, said tip portion having a lead orifice therein and a bore communicating with said orifice, and said barrel portion having a bore communicating with the bore in said tip portion, lead feeding mechanism mounted for reciprocation in the bores of said tip and barrel portions comprising a lead guide tube, a clutch having a clutch actuating sleeve, said clutch actuating sleeve being adapted to reciprocate relative to said clutch, and a spacing and aligning sleeve for said lead guide tube and having aligning engagement with the bore of said tip portion and being adapted to reciprocate relative to said bore and relative to said lead guide tube, said lead guide tube having frictional engagement with said spacing and aligning sleeve of sufficient holding force to cause said spacing and aligning sleeve to reciprocate with said lead guide tube throughout the extent of its possible travel, said clutch actuating sleeve having frictional engagement with said clutch of sufficient force to cause said clutch actuating sleeve to reciprocate with said clutch through the extent of its possible travel, said spacing and aligning sleeve and said clutch actuating sleeve having cooperating conical, non-wedging surfaces on the adjacent ends thereof whereby said spacing and aligning sleeve arrests the movement of said clutch actuating sleeve in one direction of movement and exerts a centering effect thereon.

29. In a mechanical pencil, in combination, a tubular barrel, a lead magazine longitudinally reciprocable therein and a lead guide tube connected to reciprocate with said lead magazine, a tip having a bore and a lead orifice concentric therewith, means in the lower end of the barrel for connecting said tip to said barrel and having a bore therein substantially larger than the diameter of the lead guide tube which passes therethrough, a spring fingered clutch carried by the lower end of the lead guide tube for reciprocation therewith, a clutch actuating sleeve for said clutch, and a spacing and aligning sleeve for said lead guide tube within the tip and mounted on the lead guide tube, said spacing and aligning sleeve being held in alignment solely by engagement of its outer longitudinal wall with the inner wall of the tip bore, and the longitudinal walls of the lead guide tube, the spring fingered clutch and the clutch actuating sleeve being disposed in spaced relationship with respect to the bore of the tip, the connection between said lead

magazine and lead guide tube providing for slight variations in alignment therebetween while holding the same against relative axial movement.

30. A mechanical pencil, comprising a pencil body having a lead orifice at the tip portion thereof and a bore extending therethrough, lead propelling mechanism mounted for reciprocation in said bore adapted to project the lead through said orifice, said lead propelling mechanism comprising a lead guide tube, a clutch and a clutch actuating sleeve, said clutch comprising a plurality of outwardly sprung lead gripping fingers separated by longitudinal slots and each having a lead-engaging portion, said clutch actuating sleeve being mounted on said clutch and having a finger-constricting portion and a friction surface independent of said finger-constricting portion, said friction surface being mounted on said clutch above the lead gripping portions of said fingers, and said friction surface of said clutch actuating sleeve being adapted to be frictionally gripped and carried by said clutch.

31. A mechanical pencil, comprising a pencil body having a lead orifice at the tip portion thereof and a bore extending therethrough, lead propelling mechanism mounted for reciprocation in said bore adapted to project the lead through said orifice, said lead propelling mechanism comprising a lead guide tube, a clutch and a clutch actuating sleeve, said clutch comprising a plurality of outwardly sprung lead gripping fingers separated by longitudinal slots and each having a lead-engaging portion, said

clutch actuating sleeve being mounted on said clutch and having a finger-constricting portion and a friction surface independent of said finger-constricting portion, said friction surface being mounted on said clutch above the lead gripping portions of said fingers, and said friction surface of said clutch actuating sleeve being adapted to be frictionally gripped and carried by said clutch.

5 32. A mechanical pencil, comprising a pencil body having a tip portion and a barrel portion, said tip portion having a lead orifice therein and a bore communicating with said orifice, said barrel portion having a bore communicating with the bore of said tip portion, lead feeding mechanism disposed for reciprocation in the bores of said tip and barrel portions comprising a lead guide tube, a clutch and a clutch actuating sleeve mounted in operative association with

10 15 20 25 30 35 said clutch, said clutch actuating sleeve being adapted to reciprocate relative to said clutch, and a spacing and aligning sleeve for said lead guide tube and having aligning engagement with the bore of said tip portion, said clutch and clutch actuating sleeve being disposed in the bore of said tip portion but held in spaced relation with respect to the surface thereof by said spacing and aligning sleeve, and said spacing and aligning sleeve and said clutch actuating sleeve having cooperating conical non-wedging surfaces on their adjacent ends whereby said spacing and aligning sleeve arrests the movement of said clutch actuating sleeve in one direction of movement and exerts a centering

30 35 action thereon.

JOHN P. LYNN.
